UNITED STATES PATENT OFFICE.

JOHN P. WALSH, OF NEW YORK, N. Y., ASSIGNOR OF ONE-HALF TO HENRY J. McGUCKIN, OF NEW YORK, N. Y.

LAMP-BURNER.

1,131,581.

Specification of Letters Patent.

Patented Mar. 9, 1915.

Application filed June 17, 1914. Serial No. 845,636.

To all whom it may concern:

Be it known that I, JOHN P. WALSH, a citizen of the United States, residing at New York, in the county of New York and State of New York, have invented certain new and useful Improvements in Lamp-Burners; and I do hereby declare the following to be a full, clear, and exact description of the invention, such as will enable others skilled in the art to which it appertains to make and use the same.

This invention relates to lamp burners, and has for its object to provide a device of this character of improved and simplified construction which shall be inexpensive to manufacture.

Another object is the provision of a lamp especially designed for burning gasolene and embodying a relatively adjustable wick-holding tube and a trimming and extinguishing tube.

With these and other objects in view, the invention consists in the novel construction, arrangement and formation of parts as will be hereinafter specifically described, claimed and illustrated in the accompanying drawing, in which:

Figure 1 represents a diametrical sectional view through the lamp. Fig. 2 represents a horizontal sectional view on the line 2—2 of Fig. 1. Fig. 3 represents an enlarged detail sectional view, partly broken away, of the operating means for the wick tube.

Referring to the drawing in detail, where-in similar reference numerals designate corresponding parts throughout the several views, the numeral 5 designates the body or bowl of the lamp having a convex bottom and a suitable top 6 provided with a flanged opening 7 adapted to be closed by a suitable cap 8. A weight 9 is provided in the bottom of the bowl 5 to return the bowl to its proper position when overturned. The filler 10 of asbestos is arranged in the bowl 5 over the weight 9.

The top 6 is provided with a central opening the edge of which defines an upstanding flange 11 having a vertically elongated opening adjacent its lower end into which the gear wheel 12 projects. A pair of upstanding arms 13 are secured to the cover 6 on opposite sides of the opening in the flange 7 and a shaft 14 is rotatably mounted in the upper ends of said arms and supports the gear wheel 12. A wick tube 15 is positioned

within the opening in the cover 6 and projects downwardly into the asbestos filler 10. A plurality of teeth 16 are formed laterally of the wick tube 15 and mesh with the gear wheel 12, whereby when the latter is rotated the tube 15 is raised or lowered carrying therewith the wick 17. A plurality of prongs 18^a are formed on the inner face of the tube 15 and are directed inwardly and upwardly therein for engagement with the wick 17.

A tube or sleeve 18 is telescopically engaged over the flange 11 and in its lowermost position projects a short distance above the upper edge of said flange. The outer face of the sleeve 18 at a point diametrically opposite the teeth on the tube 15 is provided with a plurality of teeth meshing with a gear wheel 19 fixed on a shaft rotatably mounted in upstanding ears 20 carried by the top or cover 6 of the body 5.

In use, the body 5 of the lamp is filled with gasolene through the inlet opening 7 and the cap 8 is subsequently secured on the flange of the opening. The wick 17 is adjusted to the desired height and lighted. The adjustment of the wick is accomplished by operation of the wheel 21 carried by the shaft 14, and the adjustment of the extinguisher and dimmer sleeve 18 is accomplished by operating the wheel 22 on the shaft carrying the gear wheel 19.

What I claim is:

1. In combination, a body having a central opening and an upstanding annular flange at the edge of said opening, an absorbent filler positioned within said body in spaced relation to the top of the latter and having a central opening registering with the first mentioned opening, a wick tube slidable vertically within said opening and terminating in spaced relation to the bottom of said body, a wick removably positioned in said tube projecting from the lower end thereof and being in contact with said absorbent filler, said upstanding annular flange having a vertically elongated slot therein, and a plurality of teeth projecting laterally from the upper extremity of said wick tube slidably seated in said vertical slot, a plurality of prongs formed integral with the inner face of said wick tube and projecting inwardly and upwardly of the latter, and a gear wheel rotatably mounted upon said body, projecting into

said vertical slots and meshing with the laterally projecting teeth of said wick tube.

2. In combination, a body having a central opening and an annular upstanding flange at the edge thereof, a wick tube slideable vertically in said annular flange, said flange having a vertically elongated slot therein, teeth projecting laterally from the upper extremity of said wick tube slidably mounted in said slot, a gear wheel rotatably supported on the top of said body projecting through said slot and connecting with said teeth, a dimmer and extinguisher sleeve slidably mounted over said annular flange, a plurality of teeth projecting later-

ally of said sleeve, a gear wheel rotatably supported on said body meshing with the last mentioned teeth, said sleeve having a vertical slot extending upwardly from the lower edge thereof and slidably receiving 20 the first mentioned gear wheel whereby said dimmer and extinguisher sleeve is secured against rotation.

In testimony whereof I affix my signature in presence of two witnesses.

JOHN P. WALSH.
